UNITED STATES PATENT OFFICE.

JACQUES SCHALL, OF PARIS, FRANCE.

POWDER BOX.

Application filed January 9, 1928, Serial No. 245,561, and in France January 14, 1927.

The present invention relates to powder boxes and more particularly to those of the type designed to deliver small quantities of powder from a main storage compartment according to the needs and desires of the user.

One of the objects of the invention is to simplify the construction of powder boxes of the special type hereinabove mentioned so that the number of parts is reduced to a minimum.

Another object is to provide an arrangement of parts which will take up a minimum amount of space.

15 A further object is to provide a form of construction in which the coacting parts of the box are free of projecting portions and interengage in a manner which prevents accidental opening of the powder magazine.

20 Still further objects will appear in the course of the detailed description now to be given with reference to the accompanying drawings in which.

Fig. 1 is a section of one form of powder 25 box taken on line 2—2 of Fig. 2;

Fig. 2 represents the same box in plan with the cover open;

Fig. 3 is a bottom view partly in section of the box illustrated in Figs. 1 and 2;

30 Fig. 4 is an end view, partly in section of the same box;

Fig. 5 is a bottom view of a second form of powder box; and

Fig. 6 is a bottom view with part of the 35 bottom removed of still another form of box.

Referring to Figs. 1 to 4, there is shown a powder magazine comprising a ring member *a* closed at one end by detachable bottom member *b* and at its other end by a perforated plate *c* resting on the upper surface of ring member *a* and free to rotate thereon. Perforations *c*^o are punched through plate *c* so as leave at least part of

45 the rough turned under edges in place. These edges function as rakes to cut into the powder when plate *c* is rotated in one direction or the other. A false-bottom *e* having a series of projecting ribs *e*^o formed thereon supports powder *f* which latter is held under compression against plate *c* by a helical spring *h*. Spring *h*, being rigidly attached to bottom *b* and to false-bottom *e* serves to prevent the latter from rotating when plate *c* is given an angular displacement. Plate *c* and bottom *b* are maintained

in assembled relation by means of a pair of telescoping casing members *n*, *o* formed so as to leave a space *m* above the horizontal upper surface of ring *a*. The peripheral portion *l* of plate *c* extends into space *m* and coacts with a toothed member *p* rigidly mounted on a shaft *q* extending through casing *n* *o*. Member *p* may be arranged to engage frictionally with *l* but preferably meshes in recesses or perforations formed in the latter in the manner of teeth. The detachable bottom member *b* may be arranged to engage with casing *o* in various ways. In the form of device shown in Figs. 1 to 4, *b* 60 is made circular and is provided with a finger or fingers *b*¹ positioned so as to pass freely through recesses *o*^o when *b* is in one position, and which engage with the edge of the casing shell when *b* is given a movement of rotation, spring *h* tending to maintain fingers *b*¹ in firm contact with the shell in any position of adjustment. The external surface of *b* may be milled as at *b*² to permit a turning movement to be effected and is further 65 provided with a groove *b*³ formed so as to be able to receive the end of a nail file or the edge of a coin. Casing *o* and bottom *b* carry reference marks showing when these elements are in opening and closed position 70 (Fig. 3). It will be noted that bottom *b* occupies only part of the bottom surface of the box and is in continuity therewith. There are no projecting parts and accidental 75 opening of the powder magazine is therefore impossible. In the form of device shown in Fig. 5, the various operating elements are similar to those shown in Figs. 1 to 4. Bottom member *b* is here arranged to have the form of a slide engaging flush with casing *o*. A recess *b*⁴ permits the detachable bottom to be removed when desired. The bottom closure of the device shown in Fig. 6 is hingedly mounted on casing *o* at *d* and is held in closed position by a spring latch 80 *d*¹. In this form of the device, as also in the device shown in Fig. 5, spring *h* shown in Fig. 1 is replaced by a star shaped spring *h*¹ attached to false bottom *e* and engaging only by friction with bottom member *b*. To 85 prevent rotation of false bottom *e* when plate *c* is given an angular displacement, guides *e*¹ are arranged to engage in an appropriately formed recess in *e*. The assemblies shown in any one of Figs. 1 to 6 are 90 completed by a cover member *i* hingedly mounted on the casing, a spring *i*¹ tending 95

to move the cover towards open position, and a spring latch assembly *j*, *j'* adapted to lock and release the cover member.

The manner in which the device operates 5 is as follows: Bottom member *b* together with false-bottom *e* are removed and powder *f* is poured into the receptacle. *b* and *e* are then forced into place, bringing powder *f* under compression against plate *c*. To remove powder from the receptacle it suffices 10 to merely rotate *q*, whereupon plate *c* cuts into powder *f* and brings a small quantity of the latter to the upper surface of plate *c* for use.

15 Devices of the type hereinabove described are known in which the number of constituent elements is considerably greater and in which bottom member *b* has salient portions which permit accidental opening of the powder compartment. The inventor does not pretend to be the first to devise a powder box provided with an angularly displaceable plate for feeding powder from a powder compartment but has improved such devices so as to (1) render them simpler, more 20 compact and more convenient for use, and (2) insure against accidental opening of the powder compartment.

What I claim is:—

30 1. A device of the class described comprising in combination a casing, a powder compartment located in said casing, a bottom closure for said compartment including a main bottom member adapted to engage 35 with said casing, a false bottom member and resilient means interposed between said main and false bottom members; a rotatable perforated plate closing the top of said powder compartment and rotatable means 40 extending through the casing and engaging with said rotatable perforated plate, said rotatable means being adapted to move the perforated plate over the powder maintained under pressure in contact with said 45 plate by the resilient means interposed between the main and false bottom members.

2. A device of the class described comprising in combination a casing, a powder

compartment located inside said casing, a bottom closure for said compartment including a main bottom member adapted to engage with said casing, a false bottom member and a spring interposed between said main and false bottom members; a rotatable perforated plate closing the top of said powder compartment, said plate having openings formed therein adjacent the periphery thereof, a toothed member positioned to engage in said openings and operable to give said perforated plate an angular displacement, and a rotatable shaft connected to said toothed member and extending through the casing, said rotatable shaft being operable to rotate the perforated plate over the powder maintained under pressure 55 against said plate by the spring interposed between the main and false bottom members.

3. A device of the class described comprising in combination a casing, a powder compartment located inside said casing, a bottom closure for said compartment including a main bottom member of lesser area than the area of the bottom of the casing, said main bottom member having means associated therewith for maintaining the same substantially flush with said casing when said member is in closed position, a false bottom member, and a spring interposed between said main and false bottom members; a rotatable perforated plate closing the top of said powder compartment, said plate having openings therein adjacent the periphery thereof, a toothed member positioned to engage in said openings and operable to give said perforated plate an angular displacement, and a rotatable shaft connected to said toothed member and extending through the casing, said rotatable shaft being operable to rotate the perforated plate over the powder maintained under pressure 65 against said plate by the spring interposed between the main and false bottom members.

In testimony whereof I have hereunto set my hand.

JACQUES SCHALL.
